UNITED STATES PATENT OFFICE.

FARNUM F. DORSEY, OF WINCHESTER, MASSACHUSETTS, ASSIGNOR TO CAMPBELL-BOSWORTH MACHINERY COMPANY, OF PORTLAND, MAINE, A CORPORATION OF MAINE.

TAKE-UP FOR SEWING-MACHINES.

No. 923,031.

Specification of Letters Patent.

Patented May 25, 1909.

Application filed July 18, 1904. Serial No. 216,942.

To all whom it may concern:

Be it known that I, FARNUM F. DORSEY, a citizen of the United States, residing at Winchester, in the county of Middlesex and 5 State of Massachusetts, have invented certain new and useful Improvements in Take-Ups for Sewing-Machines; and I do hereby declare the following to be a full, clear, and exact description of the invention, such as 10 will enable others skilled in the art to which it appertains to make and use the same.

The present invention relates to improvements in take-ups for sewing machines.

In sewing machines running at high speed 15 it is necessary that vibratory or unbalanced movement of the parts be eliminated to the greatest practicable extent. Simplicity of the mechanism and the avoidance of cam motions are also important. For these reasons it has been found that the ordinary vibratory or "fish-pole" take-up which is commonly used on machines running at moderate speeds, is unsatisfactory on high-speed machines, for not only does its unbalanced motion impart vibration to the machine, and require the use of a cam which is noisy and wears rapidly, but its operation upon the thread is uncertain, owing to the fact that it springs at the extremity of its 20 stroke rendering uncertain the setting of the stitch, which occurs at this point and requires great accuracy in the operation of the take-up.

To avoid the disadvantages of the vibratory take-up the rotary take-up was produced; *i. e.* a take-up in which the thread-drawing truck or other instrumentality is mounted on a rotary member and travels in a circle. This form of take-up may have a 30 perfectly balanced motion and avoid the use of cams; but the rotary take-up is subject, in common with take-ups of other forms, to certain requirements in the handling of the thread, to which the rotary take-up is not 35 well adapted to conform, owing to the fixed character of the path of the moving thread-truck. In high-speed sewing machines the time devoted to the operation of the take-up extends through only a fraction of a rotation 40 of the main shaft; in the machine in connection with which the present invention is 45 illustrated about 75° of a rotation are assigned to this operation. If therefore, a rotary take-up were arranged in such a machine to rotate in unison with the main

shaft only 75° of the path of motion of the moving thread truck could be utilized, and the take-up would have to be of unwieldy size in order to take up the requisite amount of thread.

In order to avoid making the take-up of 60 inconvenient size it has been proposed to arrange a rotary take-up to make two rotations to each rotation of the main shaft, and to provide means for preventing the take-up from acting upon the thread during alternate rotations. Such an arrangement permits the use of a balanced take-up of moderate size, since the available part of the path of motion of the moving thread truck is 70 twice as great as in the case of the single rotary take-up, but it is unsatisfactory for these reasons, among others, that it requires a high speed of rotation, involving increased wear and the use of gearing between the take-up and the shaft, and that the provision for interrupting the operation of the take-up during alternate rotations involves the use of cams or other mechanism inconsistent with simplicity and smooth, 75 balanced operation.

It is the object of the present invention to produce a take-up which will fulfil the essential conditions referred to without incurring the disadvantages of previously proposed 80 constructions, and to this end the invention contemplates a take-up in which the movable thread truck is actuated by an epicycloidal gearing—the term being used in its broadest sense, to define a mechanism comprising co-operating rotary members of which one or more has a motion of revolution in addition to its rotation. A take-up so constructed 85 may be arranged to move the thread truck in a trochoidal path of which the form may be varied widely according to the proportions and relative arrangement of the parts; and by selecting a path of suitable form and locating the fixed thread guides at the proper points the take-up may be arranged to take 90 up the thread in the required space of time. A take-up of this character need not be of great size, since the fixed thread guides may be located close together adjacent to a point in the path of the moving truck at which its 95 going and returning movements are on intersecting or approximating lines, so that the moving truck may act to the greatest advantage in drawing out thread. In this way also means for releasing the thread from 100 105 110

the moving truck are rendered unnecessary, since the truck, after taking up the thread, returns and passes between the fixed guides in the opposite direction, thereby backing away from the thread. Since all parts of the epicycloidal gearing have motions solely of rotation or revolution all parts may be exactly balanced so that no vibration results, however rapid the actuation of the take-up.

10 The invention is illustrated as embodied in a sewing-machine of the type described in the pending application of George E. Warren, filed March 16, 1903, Serial No. 147,888, for improvements in sewing machines, to 15 which, by permission, reference may be had for a full description thereof.

In the drawings Figure 1 is a plan view of the take-up and a portion of the sewing-machine to which it is applied. Fig. 2 is a 20 vertical section of the same. Figs. 3 and 4 are diagrams illustrating the operation of taking up.

The illustrated embodiment of the invention is constructed as follows:—

25 The moving thread truck 1, which constitutes a thread engaging device, is secured by means of an arm 2 to a pinion 3 journaled upon a crank 4 fixed to and rotated by the shaft 5 of the sewing machine. The pinion 3 engages an internal gear 6 fixed in the frame 7 of the machine. The diameter of the internal gear is exactly twice that of the pinion, so that as the crank 4 is rotated by the shaft the pinion will make one rotation absolutely for each rotation of the shaft, and the thread truck 1 will reciprocate in a straight line along a diameter of the internal gear. The weight of the crank 4 and the pinion and thread truck carried thereby are balanced by a counterpoise 8, and the weight of the thread truck and the arm 2 are balanced upon the pinion 3 by making the opposite side of the pinion heavier as shown in the section. In this way the rotary movements of the parts are perfectly balanced, and although the thread truck moves in a straight line no vibration results however rapid the actuation of the take-up.

30 The thread truck 1 co-operates with a fixed thread truck 9 and a thread lock 10 which are arranged adjacent to and on opposite sides of its path of motion so that the thread truck 1 moves between these parts, encountering the thread which is stretched between them and drawing it out into a U form, as shown in Figs. 3 and 4. As the time allotted to the operation of the taking up in the illustrated machine embraces 75° of a rotation of the shaft 5 and lock 10 are arranged to one side of the center of the take-up so that the moving thread truck shall consume 75° of a rotation in moving to the end of its path of motion after encountering the thread. On its return motion, the thread truck backs away from the thread and no means are re-

quired to release the thread from the truck. During 285° of the rotation of the shaft the movement of the movable thread truck is idle. A plate 11 is interposed between the thread and the gearing to prevent entanglement of the thread, and the stud 12 upon which the thread truck 1 is mounted projects upward through a slot in this plate. The fixed thread truck 9 is journaled on an overhanging arm 13 rising from a base plate 14 secured to the plate 11 by screws 15 engaging slots in the base plate. By loosening the screws and moving the base plate slightly the position of the fixed thread truck may be varied and the exact amount of thread taken up may be regulated. Where the time allotted to the operation of taking up is greater or less than 75° the fixed thread truck and thread lock may be moved nearer or farther from the center of the take-up, according as the time is to be greater or less.

The present invention, though illustrated in connection with a particular form of sewing machine, is applicable to many other forms; and the form of epicycloidal gearing employed to actuate the movable truck may be widely varied without departing from the invention.

Although the illustrated form of the invention is arranged to actuate the moving thread truck in a path of a particular form and to take up the thread in a specified length of time, the invention is by no means limited by these characteristics, since the value largely depends upon the fact that by slight changes in the proportions and arrangements of the parts not affecting the simplicity and balanced operation of the device, the path of motion of the moving thread truck may be varied so that the time of operation of the device may be varied to adapt it for use in different forms of sewing machines. Moreover, although the device is adapted to work satisfactorily in high speed machines when rotated once for each actuation of the needle, it may, if desired, be rotated two or more times so as to combine the advantages of the double-rotary take-up with the advantages peculiar to the present construction.

Having described the invention, what is claimed is:—

1. A take-up for sewing machines having in combination, a thread-engaging device, a movable thread-engaging device, and epicycloidal gearing for imparting a cycloidal movement to the latter, substantially as described.

2. A take-up for sewing machines having, in combination, an internal gear, a pinion rolling within the same, a thread-engaging device carried by the pinion, and a thread-engaging device co-operating therewith, substantially as described.

3. A take-up for sewing machines having,

in combination, a thread-engaging device, a movable thread-engaging device, and epicycloidal gearing for actuating the latter in a straight line, substantially as described.

4. A take-up for sewing machines having, in combination, a thread-engaging device, a movable thread-engaging device, and balanced epicycloidal gearing for imparting a vibrating movement to the latter, substantially as described.

5. A take-up for sewing machines having, in combination with the shaft of the sewing machine, a thread-engaging device, a movable thread-engaging device, and epicycloidal gearing for actuating the movable thread-engaging device connected with the

shaft so as to cause the take-up to act once during each rotation of the shaft, substantially as described.

6. A take-up for sewing machines having, in combination a thread-engaging device, a movable thread-engaging device, and balanced epicycloidal gearing for imparting a non-circular movement to the latter, substantially as described. 25

In testimony whereof I affix my signature, in presence of two witnesses.

FARNUM F. DORSEY.

Witnesses:

HORACE VAN EVEREN,
FRED O. FISH.

It is hereby certified that in Letters Patent No. 923,031, granted May 25, 1909, upon the application of Farnum F. Dorsey, of Winchester, Massachusetts, for an improvement in "Take-Ups for Sewing-Machines," an error appears in the printed specification requiring correction, as follows: In line 59, page 2, after the word "shaft," the words *the truck* should be inserted; and that the said Letters Patent should be read with this correction therein that the same may conform to the record of the case in the Patent Office.

Signed and sealed this 27th day of July, A. D., 1909.

[SEAL.]

C. C. BILLINGS,

Acting Commissioner of Patents.
